ARTICLE SUPPORT AND RELATIVELY
ADJUSTABLE GAS BURNER

Joseph B. Meriam, Lakewood, Ohio

Application September 9, 1946, Serial No. 695,586

3 Claims. (Cl. 158—99)

This invention relates to an improved burner having an improved efficiency in the use of gas by reason of adjustment to the correct distance from the bottom of the vessel or other object being heated, and wherein the adjusted position automatically governs the flow of gas required to support the flame best suited to any given position.

The object of the invention is to improve the efficiency of a gas burner by causing the burner to move toward the object to be heated as the volume of the flame is reduced, and similarly to cause the burner to move away from the object to be heated as the volume of the flame is increased.

Many experiments have proven that for each volume or height of flame there is a corresponding position of the burner that will effect most efficient transfer of heat to the object being heated.

In carrying out the present invention, I provide a simple arrangement whereby the burner may be moved toward and away from the surface or object being heated, and provide a simple orifice control which opens to allow the full flow to support the largest flame when the burner is in the appropriate position, and likewise to restrict the flow for smaller flame consequent upon the burner being moved closer to the vessel or object.

Another specific object is to provide means for moving the burner and to so arrange the burner that the same means may serve to open the gas orifice and close it to shut off the flow by a movement of the burner in the closing direction past the low flame burning point.

Other objects will become apparent in the following description which relates to the accompanying drawings, in which Fig. 1 is a plan view of my improved burner.

Fig. 2 is a side elevation partly in section.

Fig. 3 is an enlarged sectional view showing the shut-off position.

Fig. 4 is a similar enlarged sectional detail showing the full open position.

The drawings illustrate the burner associated with a support B which may correspond to a stove grid carrying a pot or pan P. It is to be understood, however, that the object or surface to be heated may be that of the inside wall of a furnace or that of many other surfaces receiving heat, and where it is practicable to effect relative movement between a burner and such a surface.

Describing the arrangement shown with the use of reference characters, the burner proper comprises a head portion 5 having conventional outlet openings 6 which may be arranged in the

perimeter of the upper surface, as desired. The head portion is merged with a tubular arm 8 which may have an opening at 9 for mixer air, and which is shown as having an integral fitting portion 10 surrounding a gas supply tube 15, and provided with an opening 20 adapted to register with an opening 25 in the tube 15 for injecting the gas into the hollow arm and mixing chamber 8 leading to the burner head.

The connecting portion 10 is in the form of a bearing embracing the supply tube 15 and fitted thereto in a manner to prevent leakage of gas while permitting relative rotary movement of the bearing portion 10 around the tube.

The size of the opening 25 with relation to the size of the opening 20 is preferably such that as the burner 5 is lowered to the position shown in broken lines in Fig. 2, the opening 20 registers with, that is, uncovers the entire jet opening 25 in the tube 15. Thus, the full flow of gas mixing with air from the opening 9, as indicated by the arrows in Fig. 4, provides a combustible mixture supporting the largest flame, indicated in broken lines at F, Fig. 2. The smaller flame, indicated in solid lines F, corresponds to the restricted flow in which the opening 20 only partially uncovers the opening 25 in the position of the burner, preferably, approximately level, or as indicated in Fig. 2.

This raising and lowering movement may be accomplished by any suitable means. For simplicity and convenience, that illustrated has been found satisfactory. Namely, the rigid projection 30, extending downwardly from the bearing portion 10 of the movable burner, is engaged by the rounded end of a screw 32 carrying a head 35 similar to the usual valve handle. This screw may be threaded through any suitable support 40 rigidly carried by the burner frame or stove parts, as may be convenient.

It will be seen that as the handle 35 is turned to move the screw inwardly, the projection 30 is swung inwardly carrying the burner upwardly around the tube 15 as a pivot. Thus, in any of several positions, varying degrees of opening through the jet openings 25 and 20 result in admitting varying amounts of gas proportionally to the flame desired for a given burner position.

Further inward movement of the screw and projection 30, through which movement the flame has been progressively diminished, moved the opening 20 above the opening 25, sealing or closing the gas supply to the burner.

Thus, it will be seen that with the actuation of one burner handle, as shown, the operating

screw member, the gas supply may be closed or may be opened partially or fully, as desired, and this same movement of the screw correspondingly positions the burner away from the object being heated, as the size of the flame increases. In the drawings I have indicated a pan P above the burner on a support B.

In addition to the mechanical convenience of effecting a burner position, corresponding to the size of the flame, by the same means which regulates the flow of gas to support that flame, definite improvements in efficiency of the burner with relation to the gas consumed are attained.

By thus varying the flame and testing the time required to raise a given amount of water a predetermined number of degrees, I have found results showing several per cent increase efficiency in effective use of B.t.u.'s in the gas fuel.

It will be seen therefore that by predetermining the position of my burner so that in its lower position where it receives maximum gas supply for the largest flame, that flame is more effectively applied to the subject such as the vessel by reason of the distance of separation between the vessel and burner.

The openings 20 and 25 are so positioned that in the medium or level position about half of the gas supply and a corresponding sized flame is then applied to the vessel. Likewise in a somewhat raised position, the smallest flame is most effectively used for slow heating.

These results are all attained by the single adjustment simultaneously moving the burner and regulating the flow of gas to correspond to the distance between burner and the object being heated.

A further point of simplicity, above mentioned, is that an additional turn of the same screw handle moves the burner from the low flame position to the full shutoff position.

Various modifications may be made in the structure, the essence of the invention being set forth in the appended claims.

Having thus described my invention, what I claim is:

1. In a device of the character described, the combination with a support for an article to be heated, and a fixed gas supply pipe having a cylindrical portion with a gas jet opening therethrough leading from the interior of the pipe, a burner head positioned beneath the support and rigid with a mixer pipe having a journal mounting unit rigid with the mixer pipe and rotatably embracing and fitting said cylindrical portion, said journal having a jet opening adapted to be moved into registering position with the first-mentioned opening and leading into the mixer pipe, the journal having a shoulder connected therewith, an adjusting screw, and a

rigidly mounting support threaded to receive the screw and positioned so that the end of the screw may engage said shoulder for moving the journal on the pipe and act to hold the burner in a given adjusted position, the location of the registering openings being such that as the burner is swung upwardly on the journal about the pipe the openings are moved out of registration shutting off flow of gas to the mixer.

2. In a device of the character described, the combination of a support for a surface to be heated, a gas supply pipe in fixed relation to said support, a burner head and mixer element communicating therewith, said mixer element including means mounted on the pipe and adapted to permit said burner head to swing toward and away from said support, registerable valve openings in the pipe and mixer portion of said element leading into the mixer when relatively moved and acting as a valve passage, a screw operated means for swinging the burner head and mixer to move the burner head toward and away from said surface and to respectively close and open the valve supply openings.

3. A gas burner head and a mixer member, a support therefor comprising a rigid gas supply pipe, said mixer member having a portion rotatably embracing said pipe, said pipe and embracing portion having openings adapted to be brought into registration when the burner is in one position and to be moved out of registration and to a closed position when the burner is in another position, a support for an object to be heated in fixed relation to said pipe, means for swinging the burner and mixer about the pipe comprising an adjusting screw and a shoulder rigid with the burner head and mixer member engaged by the screw, the positioning of said openings being such that as the burner head moves toward the support the openings are moved toward closing position, and as the burner head is lowered the openings are moved toward full registration position.
